UNITED STATES PATENT OFFICE

2,432,019

WELDING ELECTRODE HOLDER

Walter J. Koinzan, Elgin, Nebr.

Application July 20, 1945, Serial No. 606,142

1 Claim. (Cl. 219—8)

1

My invention relates to improvements in welding electrode holders, the primary object in view being to provide a simply constructed, inexpensive holder adapted for quickly and easily locking an electrode therein, or releasing the same to drop out of the holder, and which is especially designed for utilizing a metal shield for the electrode, is adequately insulated and air-cooled, and light in weight yet strong and durable.

To the accomplishment of the above, and subordinate objects presently appearing, a preferred embodiment of my invention has been illustrated in the accompanying drawing, set forth in detail in the succeeding description, and defined in the claim appended hereto.

In said drawing:

Figure 1 is a view in side elevation of my improved welding electrode holder in the preferred embodiment thereof.

Figure 2 is a view in plan.

Figure 3 is a view in longitudinal section taken on the line 3—3 of Figure 2.

Figure 4 is a view in front end elevation.

Figure 5 is a view in transverse section taken on the line 5—5 of Figure 3, and

Figure 6 is a view in side elevation of the lock nut drawn to an enlarged scale.

Referring to the drawing by numerals, my invention as shown comprises a tubular handle 1, of any suitable length and diameter, provided with longitudinal rows of air inlet apertures 2 for cooling the interior thereof with atmospheric air. A tubular steel shield 3 extends forwardly and axially from the handle 1 with its rear end slidable and rotatably fitted in said handle. The tubular steel shield 3 forwardly of the handle 1 is provided with longitudinal rows of air inlet apertures 4 therein for the same purpose as the apertures 2, and adjacent its front end with a side aperture 5 through which one end of an electrode 6 may be inserted into the shield. The handle 1 may be formed of any suitable insulation material, preferably a plastic. In the rear end of said shield 3 and suitably fixed therein is a relatively shorter bushing 7 preferably of the same material as the handle 1. A tubular steel electrode-holding member 8 extends through the bushing 7 and is suitably fixed therein with its rear end projecting for a short distance out of said bushing 7 and its front end terminating opposite the aperture 5 and closed by a cap piece 8' also of steel, the capped end of said member being provided with a side opening 9 therein registering with a similar opening 10 in the cap piece 8' and both openings registering with the aperture 5 so that the elec-

2

trode 6 inserted through said aperture may be projected into the capped end of said member with its inner end opposed flat against the front of the cap piece 8'.

5 A generally tubular metal cable-clamping element 11 provided with an enlarged front end 12 fitting in the handle 1 is fixed in said handle in suitably spaced relation to the rear end of said electrode-holding member 8 by means of a screw 13 extending through said handle 1 into the enlarged end 12 of said element with its head countersunk in said handle. The bore 14 of the element 11 is threaded to an enlarged transversely concave socket 15 provided in the rear end of said element in the axis of said bore and into which the split ends 16 of the usual insulated power cable 17 may be spread and clamped by means to be described. The bore 14 of said element 11 is of substantially the same diameter as the internal 10 diameter of the electrode-holding element 8. A combined cable and electrode-clamping rod 18, preferably of steel, is threaded into the rear end portion of the electrode-holding member 8 and into the bore 14 of the cable-clamping element 11 and provided with a tapered rear end 19 adapted, when said rod 18 is turned into said element 11, to enter between the split ends 16 of the power cable 17 and spread the same apart against the wall of the socket 15 to clamp said ends in said socket. 15 The combined cable and electrode-clamping rod 18 is provided with a reduced front end section 19 adapted, when said rod is turned into the electrode-holding member 8, to engage the inner end of the electrode 6 and clamp said end against the front of the cap piece 8'. A jam nut 21 is provided on said rod 18 for turning against the front end of said element 11 to lock said rod in cable-clamping position, said jam nut being provided with fingers 22 overlying the rear end of said member 20 8 and for use in turning the nut.

40 Referring now to the use and operation of the described invention. To assemble the same, the split ends 16 of the power cable 17 are first positioned in the socket 15 and the combined cable 45 and electrode-clamping rod is turned into said element to insert the tapered end 19 thereof between said ends 16 and clamp the same in place. The jam nut 21 is next turned against said element to lock said rod in clamping position. The 50 cable-clamping element 11 is then inserted together with said rod 18 into the handle 1 and secured therein by the screw 13. The shield 3 is then grasped by one hand and said rod 18 turned into the threaded end of the electrode-holding member 8 until the shield 3 is drawn into

the handle 1 a suitable distance such that the electrode 6 may be inserted in the manner described in front of the rod section 20. With the electrode 6 inserted, the handle 1 is turned further to tighten the rod section 20 against said electrode and clamp the same in place. As an optional procedure, the shield 3 may be rotated to extend said rod 18 into said member 8. As will be seen, after the rod section 20 is in clamping position a slight turn of the handle 1, or the shield 3, will suffice to release the electrode 6 so that it will drop out of the holder. Conversely, a slight turn of said handle 1 will clamp a new electrode 6 in place.

The foregoing will, it is believed, suffice to impart a clear understanding of the structure, use and advantages of my invention without further explanation.

Manifestly, the invention, as described, is susceptible of modification as regards structure and combination of parts without departing from the inventive concept, and right is herein reserved to such modifications as fall within the scope of the appended claim.

What I claim is:

An electrode holder comprising a tubular handle of insulation material, a cable-clamping member in said handle detachably secured therein and provided with an internal socket therein adapted to receive a split end of a power cable extended into the rear end of the handle, a combined cable and electrode-clamping rod having a portion threaded into said member with an end interposed between said split ends of the cable to clamp said ends in said socket and including an electrode-clamping opposite end portion extending out of the front end of said handle, a tubular perforated shield surrounding said rod with one end rotatably and slidably fitted in said front end of the handle and provided with a side

opening therein adjacent the opposite end thereof, and means in said shield coacting with said threaded portion of said rod when the shield is rotated to clamp an electrode against said clamping opposite end of said rod, said means comprising a tubular electrode-holding member in said shield fixed thereto in surrounding relation to said rod and spaced from said shield to form an air space between said shield and said electrode holding member, said holding member having a front end side opening in one side thereof solely for the insertion of one end of an electrode therethrough into the electrode-holding member, and also having a closed front end between which and said clamping end of said rod the electrode is adapted to be gripped, said electrode holding member being threaded onto said threaded portion of said rod for adjustment along the same when said shield is rotated to move the closed end of the holding member toward said clamping end of said rod.

WALTER J. KOINZAN.
